UNITED STATES PATENT OFFICE.

ROLLYN H. BAKER, OF DAYTON, OHIO.

BOX-OPENER.

1,140,016.

Specification of Letters Patent.

Patented May 18, 1915.

Application filed March 21, 1914. Serial No. 826,359.

To all whom it may concern:

Be it known that I, ROLLYN H. BAKER, a citizen of the United States, residing at Dayton, in the county of Montgomery and State 5 of Ohio, have invented new and useful Improvements in Box-Openers, of which the following is a specification.

This invention relates to improvements in box openers and has for its object the provision of a simple and cheap device that is readily reset when the cover is replaced and that is thoroughly efficient and reliable in operation and which moreover is not likely to casually open the box.

15 To this end the invention consists in combining with a box comprising a pair of members arranged so that one partly overlaps the other, a triangular opener pivotally mounted on the overlapped member and 20 presenting a straight edge to the edge of the overlapping member, the pivot of said opener being at a point between its upper corners and the lower corners of said opener being outturned to form a handle as hereinafter described and claimed.

In the accompanying drawings:—Figure 1 is a perspective view of a blacking box provided with an opener constructed in accordance with my invention. Fig. 2 is an 30 elevation of the same showing the opener in the act of releasing the cover of the box. Fig. 3 is a vertical transverse sectional view of the same.

The box may be of any suitable construction embodying a pair of members arranged so that one member partly overlaps the other. For the purposes of this specification I show my box opener attached to an ordinary blacking box comprising a circular 35 body 1 and a circular cover 2 the latter having a skirt 3 which partly overlaps the body and is provided with an outturned flange 4. The body of the box also has a bead 5 on which said flange bears.

Copies of this patent may be obtained for five cents each, by addressing the "Commissioner of Patents, Washington, D. C."

In accordance with my invention I provide a triangular opener 6 which may be made of any suitable sheet metal and which is pivoted as at 7 to the box body, the pivot being arranged at a point below and between the upper corners 8 of the opener. 45 Thereby the opener is arranged to present a straight edge at its upper end which bears against the under side of the flange of the box cover. The lower corner of the opener is outturned to form an operating handle 9. 50 55

To release the cover it is only necessary to partly turn the opener in either direction so as to cause one of the upper corners thereof by engagement with the flange of the box cover to act as a cam and pry up one side 60 of the cover, thereby releasing the latter.

Having thus described my invention, I claim:—

In combination with a box comprising a pair of members arranged so that one partly 65 overlaps the other, a triangular opener pivotally mounted on the overlapped member and presenting a straight edge to the edge of the overlapping member the pivot of said opener being at a point between its upper 70 corners and the lower corner of said opener being outturned to form an operating handle, the overlapped member having a bead thereon coincident with the upper edge of the opener and the overlapping member 75 having an outturned flange at the edge of its skirt to bear on and overhang the straight edge of the opener when the latter is in normal position.

In testimony whereof I affix my signature 80 in presence of two witnesses.

ROLLYN H. BAKER.
